UNITED STATES PATENT OFFICE

2,009,403

BATTERY TERMINAL

George Koops, Holland, Mich.

Application October 28, 1933, Serial No. 695,608

1 Claim. (Cl. 173—259)

This invention relates to a battery terminal.

One of the primary advantages of my device resides in its outwardly extended slotted ears whereby the bolt means, which clamps it in place, may be quickly and easily removed from its more or less corroded seat by a simple prying operation and thus much time is saved as well as annoyance avoided.

Another feature of my invention resides in the diverging outer surfaces of the ears whereby tightening of the bolt causes it to slide inwardly and prevents any accidental releasing movement from occurring.

Yet another advantage resides in the provision of lug means for preventing rotation of the head of the bolt.

Other advantages will become apparent as the description proceeds.

In the drawing:—

Fig. 1 is a plan view of my battery terminal as applied to the post of the ordinary storage battery.

Fig. 2 is a side view of the battery terminal with the clamping bolt located therein.

Fig. 3 is a side view of Fig. 1, partly in section.

Fig. 4 is a plan view of my device with the clamping bolt removed.

Fig. 5 is a side view of Fig. 4.

Fig. 6 is a perspective view of the clamp. Similar numerals refer to similar parts throughout the several views.

Referring particularly to Figs. 1 and 3, 10 indicates a storage battery having the usual tapered post 11 extending upwardly therefrom.

35 My device is formed of a body portion 12, such being of substantially cylindrical shape, and being formed of brass or the like which may be coated with lead or electro-plated. It is to be understood that the body is formed of metal having more or less resiliency whereby it will normally spring outwardly to such a size as to permit it to be readily slid to its operative position over the battery post 11.

40 A socket member 13 is integrally formed with the body portion 12 and receives a conductor member 14 therein. See Figs. 1 and 2.

At the opposite side of the body ears 15 and 16 are formed, these ears having slots 17 and 18 respectively formed therein.

50 As clearly shown in Fig. 3, these slots are parallel to one another and extend angularly upward whereby a tool, indicated at 19 in Fig. 3,

may be inserted adjacent the post 11 so as to pry the fastening bolt 20 out of the slots.

A projection 21, see Figs. 4, 5 and 6, extends outwardly from the bottom portion of the ear 16 and contacts against the head of the bolt 20 when the bolt 20 is located in the slots and prevents turning of the bolt. Thus the nut on the bolt may be tightened to cause the ears 15 and 16 to approach one another and to tightly clamp the post 11 therebetween.

The outer surfaces 22 and 23 of the ears 15 and 16 extend outwardly angularly with respect to one another and thus exert pressure on the head of the bolt and the nut thereof, see Fig. 1, to cause it to slide inwardly towards the battery post 11 and thus absolutely prevent the bolt from working out accidentally. This is a very important feature of my invention and it is to be noted that the ears 15 and 16 are resilient and exert an outward pressure at all times and after the bolt 20 has been removed, as by means of the tool 19 shown in Fig. 3, that these ears will spring apart, see Fig. 4, and thus the body 12 will be readily insertable upon the battery post 11.

Having thus revealed this invention, I claim as new and desire to secure the following combinations and elements, or equivalents thereof, by Letters Patent of the United States.

I claim:—

In combination with a battery post having a substantially cylindrical upper end, of a battery terminal having a body extending partly around the upper end of the post and terminating in a socket at one side and in ears at the opposite side, 35 the ears being spaced apart sufficiently to permit the insertion of a screw driver therebetween, the outer faces of said ears diverging outwardly from each other when the same are in operative position as well as inoperative position, the 40 ears also having slots therein, the slots extending inwardly and downwardly and terminating short of the post whereby a screw driver may be inserted between the post and the closed ends of the slots, a bolt received in said slots, a nut 45 engaged thereon, the head of the bolt engaging against the outer face of the other ear for the purpose described, and a lug positioned on the outer face of one of said ears, said lug having a surface substantially parallel to the sides of 50 the adjacent slot.

GEORGE KOOPS.
